UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE BEARING FOR RAILWAY-CARS.

1,360,783.

Specification of Letters Patent.

Patented Nov. 30, 1920.

Application filed July 5, 1919. Serial No. 308,827.

To all whom it may concern:

Be it known that I, JOHN F. O'CONNOR, a citizen of the United States, residing at Chicago, in the county of Cook and State of Illinois, have invented a certain new and useful Improvement in Side Bearings for Railway-Cars, of which the following is a full, clear, concise, and exact description, reference being had to the accompanying drawings, 10 forming a part of this specification.

My invention relates to improvements in side bearings for railway cars.

One of the objects of my invention is to provide a simple and efficient side bearing. 15 Another object is to provide a gravity centering side bearing of few parts. Further objects will appear from the description of the invention hereinafter following.

In the drawings forming a part of this specification, Figure 1 is a cross section of the bolsters of a railroad car showing my improved side bearing mounted therebetween. Fig. 2 is a horizontal sectional view taken on line 2—2 of Fig. 1. And Fig. 3 is a vertical section part in end view, the section line being shown at 3—3 in Fig. 1.

Referring to the drawings, the numeral 10 indicates a body bolster of a railroad car, only the lower portion thereof being shown, 30 and 11 the truck bolster, only the upper portion being shown. The side bearing consists of three parts—the base member 12, the roller or anti-friction element 13, and the bearing plate 14. The base member is of a general hollow rectangular shape open at top and bottom and provided with the lugs 35 15 by means of which it is secured to the truck bolster 11 by suitable means—as, for instance, the rivets 16—16. The end walls 40 17—17 of the base member are each provided with a slot 18 for the discharge of dirt and dust. One of the end walls—as, for instance, that shown at the right-hand in Fig. 1 of the drawings—is provided with a slot 19 45 for the insertion and withdrawal of the bearing plate 14 in the manner hereinafter described. The bottom of the base member is partially closed by the lower plates 119—119 50 there being provided between them the vertical opening 20 for the insertion of the roller within the base member in the manner hereinafter described.

The roller or anti-friction element consists of a portion of general cylindrical 55 shape referenced 21, each side of which is

provided preferably at its center with a groove 22. At either end and depending over the edges of the bearing plate 14 is a counter balance 23, preferably an integral part of the member 21, and at the ends thereof are the projecting members 24, each of said members being preferably pentagonal in shape, serving as centering guides for the anti-friction members as they are received in the recesses 25 in each side wall 26 of the base member, the conformation of the said members being such that in all positions of the anti-friction member in its longitudinal movement within the base member the said members 24 substantially span the recesses 25. The recesses 22 in the roller permit a narrower opening 20 than would be had were it necessary to insert the roller through the bottom portion of the base member in assembling without the said recesses 22 60 65 70 75 80 85 90 95 100 105 110

therein. The side walls 26 of the base member are provided along their upper edge and forming the upper end of the recesses 25 with the flanges 27, which prevent the upward withdrawal of the anti-friction element from the base member. In assembling the parts, the anti-friction member is passed through the opening 20 in the bottom of the base member until it is in its operative position. The said opening 20 is most restricted between the bottom portions 119 of the base member, and, as will be observed in Fig. 2 of the drawings, at either side of said bottom portions the base member is open to permit the reception and movement therein of the counter balances 23 hereinafter described. The grooves 22, as hereinbefore mentioned, permit the passage of the roller through the opening 20, which is of suitable width therefor. When the roller is in its position within the base member, the bearing plate 14 is inserted through the opening 19 until it rests upon the bottom portions 119 of the base member, as most clearly shown in Fig. 1 of the drawings, and when in its position is secured therein by suitable means—as, for instance, the cotter key 28. The base member is then secured in its position upon a car bolster. In disassembling the parts, the reverse of this operation is followed. On movement of the anti-friction element, which will occur on engagement of the upper bolster 10 against the anti-friction element, the same rolls upon the bearing plate 14, and if the 110

movement is such as to roll, for instance, to the right, upon full rolling movement the parts will assume the position shown by the dotted lines referenced 29 in Fig. 1 of the drawings, with the anti-friction element on full movement to the right in engagement against the adjacent end wall 17 of the base member 12. It will also be observed that in the normal position of the anti-friction element, as shown in Fig. 1 of the drawings, the same rests upon the bearing plate 14 above the portion of the opening 20 in the base member between the bottom sections 119 thereof, and, by reason of this spanning by the bearing member 14 between the portions 119, a slight yielding of the bearing plate 14 may be had, thus tending to minimize the shocks occasioned by the sudden engagement of the body bolster against the anti-friction element.

20 I claim:

1. In a side bearing for railroad cars, in combination, a base member, an anti-friction member therein and a removable bearing plate therefor, the anti-friction element comprising a cylindrical portion and counter balances extended therefrom, the bearing plate engaging the cylindrical portion and passing between said counter balances, the said base member having an opening in its bottom, the plate bridging said opening, the said opening being of a lesser width than the diameter of the cylindrical portion of the anti-friction element, the said cylindrical portion being provided with grooves to permit its passage through said opening.

2. In a side bearing for railroad cars, in combination, a base member, an anti-friction element therein, and a removable bearing plate therefor, the anti-friction element having a cylindrical portion, counter balances depending therefrom and centering guides extended from said counter balances, the base member being provided with recesses to receive said guides, the base member having a restricted opening in its bottom, the bearing plate spanning said opening and supporting the anti-friction element.

3. In a side bearing for railroad cars, in combination, a base member, an anti-friction element therein and a bearing plate therefor, the anti-friction element comprising a cylindrical member, counter weights depending therefrom on either side of the bearing plate and guiding members extended from said counter weights, the base member being provided with recesses to receive said guiding members.

5 60

4. In a side bearing for railway cars, in combination, a base member, an anti-friction element therein, and a bearing plate therefor, the anti-friction element comprising a cylindrical portion and having counter weights depending therefrom, the bearing plate passing between said counter weights, the said base member being open at its bottom and provided with extensions therein to support the ends of said bearing plate.

5. In a side bearing for railroad cars, in combination, a base member, an anti-friction element mounted therein and a bearing plate for said anti-friction element, the 75 anti-friction element comprising a cylindrical portion, counter weights depending therefrom, the said counter weights being provided with epicycloidal guiding extensions, the base member being provided with 80 recesses to receive said extensions.

6. In an anti-friction bearing of the character described, the combination with a hollow substantially rectangular base member open at the bottom and provided on its interior at the bottom with opposed inwardly extending sections, said sections being of reduced width horizontally at their inner ends with a space therebetween; of an anti-friction element disposed within said base member, said anti-friction element being provided with parallelly extending grooves on opposite sides thereof vertically aligned with said extensions of reduced width whereby the anti-friction element may be inserted 95 vertically through the bottom of the base member between said extensions; co-operating means on the anti-friction element and the base member preventing removal of the anti-friction element from the top of the 100 base member; and a plate insertible beneath the anti-friction element and arranged to form the bearing surface therefor when the parts are assembled.

In witness that I claim the foregoing I 105 have hereunto subscribed my name this 6th day of June, 1919.

JOHN F. O'CONNOR.
